William B. Dobson of Polk County, North Carolina
Sellers Patent.

The Schedule referred to in these Letters Patent, and making part of the same (containing)
a description in the words of the said William B. Dobson himself of his Improvement
called the "Blacksmith's Assistant Striker."

To all whom these presents shall come. Be it known that I William B. Dobson
of the United States in the County of Polk and State of North Carolina, have invented
a new and useful improvement in the "Blacksmith's Assistant Striker," and that the
following is a full and exact description of the construction and operation of the said
machine as invented or improved by me, to wit: The foundation of this machine
consists of five sills, five by four inches square, namely, two side sills, six feet long,
two end pieces and one cross piece four feet long, formed into a frame by means of the end
sills and cross sill (which is 18 inches from the back end of the frame) being let into the
side sills with tenons. On each of the two side sills stand two upright supports, four
inches square by means of tenons and mortises into the middle of the side sills, which up-
right supports are five feet high. One foot from the top of these upright supports ex-
tending from one to the other is a cross beam thereby five inches square to make straddled
the upright supports at and for purposes hereafter mentioned. Three feet from the
bottom of the frame extending from one of these upright supports to the other and let into
each of said upright supports with iron judiciously quartered of an inch in diameter
dovetailed into the end thereof is the hammer scale, through which passes the far end of the
helve of the hammer, and this hammer scale should be about nine inches square and
this square left one foot long at the post, this which passes the helve and the end turned
down to about four inches in diameter. The helve of the hammer is about five feet long
round or square as may direct extending thro the scale nine inches made thicker
where it joins the scale and gradually tapering towards the hammer. The hole in the
hammer scale through which passes the helve of the hammer is widest in front. The end
of the helle which passes thro the scale should be round and tapering, from a taper-
ing should to the end gradually after the manner of the scale of a wagon. This tapering part
of the helle should be no more than twenty inches long, should correctly fit the hole in the
scale, but not so tight as to prevent its turning round in the hole when necessary.
The helle of the hammer should pass thro the scale loosely for the purpose of shifting (by turning
it)

The face of the hammer should be anterior to hammer head on the middle side, then the shaft for instance to make a horse shoe is made from in any proportion in mass, following to set, on the front part of the axle, for which pass the end of the helve is firmly spliced with iron plates, a round piece of timber one inch thick which may be made by sawing off the end of a round piece of timber, a wheel of one inch thick or long and nine inches in diameter having a hole during the hole in the axle & with like tapering. And in this wheel of timber spliced to the front of the axle is drawn an iron band: two inches broad and of suitable thickness, which will throw the band one inch over the edge of the timber it surrounds, and on the front edge of the band is cut notches upward down and then the helve of the tapering shoulder through running a cross round bolt of iron half inch thick and ten inches long made from & fast in the helve & to get the notches in the band of iron above and below, as it may be turned round one way or the other. and the rod or bolt of iron is confined in whatever notches of the iron band it may be fast, by means of a steel wire spring proper judgment the tapering end of the helve, which extends nine inches through the axle, this spring is wrapped in iron maner round the end of the helve from the axle nearly to the end near the end of the helve, is an oblong square mortise half way down which extends in its winding the steel wire spring & a tapering wedge is then driven into this mortise which puts the spring in such constant action, last to confine (by driving back the helve up hard to its shoulder) the said rod into the notches. The helve of the hammer should pass thro the left end of the axle, about ten inches from the end as it fronts the workman. The hammer should weigh about ten pounds, but may be varied in size, to suit the fancy of the workman. On the centre of the back side stands fitted into the side a firm upright post, four inches square about one foot high, into which is let a square treadle extending toward the anvil about three feet six inches, thereby two inches square. Thus the left hand middle upright supported below the axle is mortised an oblong square mortise & in this mortise is fitted another treadle extending across the frame from one support nearly to the other passing just above the first treadle: near the end of this treadle where it looks in the supports and on the top thereof is crowded a steel or wooden spring so as elevate the other end which when it meets the upright supports on the other side is considerably above the second treadle, on the middle cross beam the upright end thereof as it fronts the workman, stands another upright steel post first four inches square and about eighteen inches high, into which is fitted a third treadle extending from passing the right hand side of the anvil block soon weight

fitting and resting on the end of the second mentioned treadle. This third treadle should be three inches at one end and tapering out towards the workman to about two inches square. This third treadle should be so fixed into its post as to clear out its end near the workman. On the top of each of the two middle upright supports is framed with tongue groove and fir, a piece of timber four inches square, extending back three feet ten inches, inclining downwards. The ends of these pieces last mentioned are united with tongue and mortise, by two pieces of timber four by one inch broad, one of them being at the end and the other one foot from it, covering the two supports. On the lower side of this first cross piece is secured a steel or suitable wood spring about four feet long extending gradually upward, over the axle and resting on the nearest cross piece. At the middle of the axle are two staples or hooks of iron one driven into the upper side of the axle and the other directly below. The lower staple in the axle is forced up to the spring above by means of a thin plate or bar of iron about nine inches long with about five holes in it equidistant from each other and chains of suitable length at each end. The upper chain having a hook to its lower end by means of which and the holes in the iron plate, the hammer may be lowered or elevated toward the upper spring. The staple in the upper part of the axle is in like manner secured to the first or lowest treadle. On the middle side about ten inches from the left end thereof as it fronts, the workman stands on upright post four inches square and near four feet high. This which is mortised a hole and in it is fitted the end of a rabbit which passes from this a mortise in the cross piece covering the supports, at top over the hammer, which the hammer when carried up by the upper spring strikes, is stopped, or rather forced back. On the supports on the right hand side as it fronts, the anvil, and just above where the first described spring on the second treadle touches it is bent a hole in which when the workman would strike fast, should be driven in iron bar against which this spring works and affects greatly in rapid striking. There is a fourth treadle fixed transversely at the end of the third treadle. The end of which from the anvil is fastened to a post or stake in the floor and the other which extends to the right foot of the workman passing the end of the third treadle about one foot, is joined to the end of the third treadle by means of an iron rod fast in the post last mentioned extending up through the end of the third treadle and secured by a screw cap, when this treadle is brought down by the foot brings down the hammer to the anvil. The

The face of the hammer is to enable the workman to hammer his iron hammer at one side then the other for instance to make a hinge. This is made firm in any one position in manner following to wit: on the front part of the axle, the wheel passes the end of the hub is firmly gilded with iron spikes. A round piece of timber one inch thick which may be made by sawing off the end of a round piece of timber, a wheel of one inch thick or long and nine inches in diameter having a hole in the axle & with like tapering. And in this wheel of timber is fitted to the front of the axle is drawn an iron band, two inches broad and of suitable thickness, which will throw the band one inch over the edge of the timber it surrounds, and on the front edge of the band is cut notches up and down and then the hole of the tapering shoulder thereof run a compound bolt, of iron half inch thick and ten inches long made firm & fast in the hub & to fit the notches in the band of iron above and below, as it may be turned round one way or the other. and the rod or bolt of iron is confined in whatever notches of the iron band it may be fast, by means of a steel wire spring wrapped round the tapering end of the hub, which extends nine inches through the axle, this spring is wrapped in iron manner round the end of the hub from the axle nearly to the end near the end of the hub, is an oblong square mortice half way down which extends in its winding the steel wire spring & a tapering wedge is then driven into this mortice which puts the spring in such constant strain, last to confine (by driving back the hub up hand to its shoulder) the said rod into the notches. The hub of the hammer should pass thro' the left end of the axle, about ten inches from the end as it fronts the workman. The hammer should weigh about ten pounds, but may be varied in size to suit the force of the workman. On the centre of the back sill stands fitted into the sill a firm upright post, four inches square about one foot high, into which is let a square treadle extending towards the anvil about three feet six inches, thereby two inches square. Thro' the left hand middle upright supported below the axle is morticed an oblong square mortice & in this mortice is fitted another treadle extending across the frame from one support nearly to the other passing just above the first treadle, near the end of this treadle where it works in the support and on the top thereof is crooked a steel or wooden spring so as elevate the other end which when it meets the upright supported on the other side is considerably above the second treadle. On the middle of the sill near the upright end thereof as it fronts the workman, stands another upright steel post four inches square and about eighteen inches high, into which is fitted a third treadle extending from passing the right hand side of the anvil block down upright

fit long and resting on the end of the second mentioned traddle. This third traddle should be three inches at one end and tapering out toward the workman to about two inches square. This third traddle should be so fixed into its post as to elevate its end near the workman. On the top of each of the two middle upright supports, is framed with tongue and fin, a piece of timber four inches square, extending back three feet ten inches, inclining downward. The ends of these pieces fastened are united with tongue and mortise, by two pieces of timber four by one inch broad, one of these pieces at the end and the other one foot from it nears the two supports. On the lower side of this first cross piece is secured a steel or suitable wood spring about four feet long extending gradually upward, over the axle and resting on the nearest cross piece. At the middle of the axle are two staples or hooks of iron one driven into the upper side of the axle and the other directly below. The lower staple in the axle is ground up to the spring above by means of a thin plate or bar of iron about nine inches long with about five holes in it equidistant from each other & chains of suitable length at each end. The upper chain having a hook to its lower end by means of which and the holes in the iron plate, the hammer may be lowered or elevated toward the upper spring. The staple in the upper part of the axle is in like manner geared to the first or lowest traddle. On the middle side about ten inches from the left end thereof as it fronts the workman stands an upright post four inches square and near four feet high. This which is mortised a hole and in it is fitted the end of a rabbit which passes front this a mortise in the cross piece uniting the supports, at top over the hammer, which the hammer when carried up by the upper spring strikes, is stopped, or rather forced back. On the supports on the right hand side as it fronts the anvil, and just above where the first described spring on the second traddle touches it is found a hole in which when the workmen would strike fast, should be driven an iron bar against which this spring works and abates greatly in rapid striking. There is a fourth traddle fixed transversely at the end of the third traddle. The end of which from the nail is fastened to a post or stake in the floor and the other which extends to the right foot of the workman passing the end of the third traddle about one foot, is joined to the end of the third traddle by means of an iron fast in the post traddle and extending up through the end of the third traddle and secured by a screw cap. This traddle brought down by the post brings down the hammer to the anvil. The

front end of the machine being laid on a flat thin piece of timber with holes bored in the side near the nail and a short piece of timber being mortised into the front all extending over these holes, having also a hole in it over the lower holes. The front part of the striker may be easily moved from side to side with a small iron or wooden lever. This machine may be made of greater or less dimensions by changing the proportions above described. of this machine. the hammer its
hollow the scale the simple principle of making it with a lever and the lower part
of the frame are old. the balance being the improvement. that the above de-
scribed machine and all and every part thereof is new except as above. I witness
that the above is a true specification of how how to set my hand April
1st 1844
